(57) **CLAIM**

The ornamental design for an electrode for an electropsychometer, as shown and described.

DESCRIPTION

FIG. 1 is a front and left end perspective view of an electrode for an electropsychometer in accordance with the present invention;

FIG. 2 is a left end view thereof;

FIG. 3 is a front side view thereof, the rear side view being the same;

FIG. 4 is a top plan view thereof, the bottom plan view being the same;

FIG. 5 is a right end view thereof; and,

FIG. 6 is a rear and right and perspective view thereof.
